DRIVE FOR CLOTH SPREADING MACHINES

Mortimer Ronald Katz, Montreal, Quebec,
Canada

Application June 19, 1948, Serial No. 33,960

3 Claims. (Cl. 105—144)

1

The invention relates to improvements in a drive for cloth spreading machines, as described in the present specification and illustrated in the accompanying drawings that form a part of the same.

The invention consists essentially of the novel features of construction as pointed out broadly and specifically in the claims for novelty following a description containing an explanation in detail of an acceptable form of the invention.

The objects of the invention are to devise a drive mechanism for the operation of a cloth spreading machine and with which is incorporated a seat for the operator; to facilitate the operation of spreading cloth on cutting tables and to speed up such operation; to eliminate fatigue to the operator or supervisor of the cloth spreading machine presently caused by this person having to walk alongside of the spreading machine as he or she inspects the cloth for irregularities during the spreading operation; to furnish a drive for a cloth spreading machine that will operate same with a multiple of the speed obtainable with electromagnetic machines in present use; to equip an ordinary hand driven cloth spreading machine with an electric drive so mounted and arranged as to travel along with the spreading machine and by which the spreading machine may operate fully automatic; to construct a drive for cloth spreading machines consisting of comparatively few and simple parts, easy and economical to manufacture; and generally to provide a drive for cloth spreading machines that is efficient in its use.

In the drawings:

Figure 1 is a side view of a cloth spreading machine mounted on the cutting table and showing the drive as attached thereto.

Figure 2 is a plan view of Figure 1.

Figure 3 is an end view of Figure 1.

Figure 4 is a view as taken on the line 4—4 in Fig. 3.

Figure 5 illustrates the invention as arranged for the use of D. C. current.

Figure 6 is a side view of the drive showing same for the use of A. C. current.

Like numerals of reference indicate corresponding parts in the various figures.

The present invention as hereinafter described and illustrated is particularly adapted for use in the clothing and allied industries for attachment to an ordinary hand driven cloth spreading machine, converting same to a power driven machine whereby the operator or supervisor of the cloth spreading operation is enabled to "ride" the machine back and forth during its operation in-

2

stead of walking back and forth with it as is at present the case.

Referring to the drawings, the drive for a cloth spreading machine, consists of a carrier or carriage, as indicated by the numeral 10, adapted to be attached to a cloth spreading machine 11 as mounted on a cutting table 12, and mounting an electric motor 13 and other mechanism supplying the motive power therefor.

- 10 An acceptable and preferable type of carriage is in the form of a rectangular-shaped framework of angle iron, piping or metal rods, and is of predetermined length, width and height but being considerably less than the height of the cutting table.
- 15 The framework or carriage 10 is provided with wheels, preferably a pair, 14 and 15 respectively, located at the bottom of same on one side thereof, one wheel being located adjacent to each end thereof. The shaft 16 of the front supporting wheel 15 extends across the bottom of the framework and is journaled in pillow blocks 17 and 18 fixedly secured one to each of the bottom longitudinal side members 19 and 20, the shaft extending beyond the inner longitudinal side member 19. The rear or driving wheel 14 has its shaft 21 journaled in the pillow block 22 extending therethrough and connecting with a rotatable shaft 23 extending out from a speed reduction unit 24 by means of a coupling 25.
- 20 The wheel shafts 16 and 21 extend a predetermined distance out from the inner longitudinal side member 19 to mount the wheels 14 and 15 in perfect alignment with one another. These bottom or support wheels 14 and 15 are adapted to engage with a rail 26. This rail or track 26 is preferably in the form of an angle iron fixedly secured to the floor and extending the length of the cutting table 12 and is positioned on the floor of the room adjacent to the table, the wheels running on the upturned flange of the angle iron rail, which positions the wheels and the carriage clear of the floor.
- 25 Upper or retaining wheels 27 and 28 extend out from the upper inner longitudinal side member 29, being secured to the outwardly extending brackets or rods 30 and 31, and these wheels are positioned horizontally at the end of their respective bracket and are located adjacent to each end of the carriage similar to the lower or support wheels 14 and 15. The retaining wheels engage with an angle iron rail or track 32, which rail is fixedly secured to brackets or supports 33 which are fixedly secured to and extend out from the side of the cutting table, positioning the upper rail 30 out from the table. This upper rail extends the

length of the table, and the wheels 27 and 28 are positioned back of the rear flange of the rail and against same to move therealong.

The motor 13 is movably mounted on a base 34 which rests on the bottom longitudinal side members 19 and 20 and suitably and fixedly secured thereto. The motor is supplied with electric power by means of a feed rail 35, or similar conductors, secured to the ceiling or to the cutting table, the power cable 36 being fed through a pipe 37 secured to the carriage 10 and connected to a controller 38 mounted on the carriage, and onto the motor. This controller 38 is actuated by the operator for starting, stopping and reversing the motor.

The cloth spreading machine 11 is mounted on rails 39 and 40 fixedly secured to the top of the cutting table 12 and extending the length thereof. The drive or carriage 10 is secured to the cloth spreading machine by means of a hinge or metal strap 41 secured to the bottom portion of the spreading machine and to the top portion of the carriage 10. This connecting member 41 is flexible or so arranged as to absorb any irregularities which might exist or develop in the relative position of the rail 26 and the cutting table 12.

The base 34 hereinabove referred to, is the base block of a mechanical speed controller, the speed controller comprising this base 34 and the variable speed pulley 42 which is connected to the motor. The variable speed pulley 42 is of the type that is composed of two cone shaped flanges slidably mounted on the shaft and held together by a spring. The speed controller unit is connected to a speed reducer 24 suitably located at the rear of the carriage by means of a belt 44 connecting the variable speed pulley 42 to a wheel or pulley 45, the pulley 45 being connected to the rotatable shaft 23 of the speed reducer 24 which in turn is connected to the rear or driving wheel 14 of the carriage, as hereinabove described.

The operating mechanism of the speed controller consists of a threaded screw 45 extending into the base 34 through an aperture 47 therein and having its inner end engaging a nut secured on the underside of the motor 13, a sprocket 48 being secured at the outer end of the threaded shaft 46. A shaft 49 having one end secured in a gear box 50, located at the rear and top of the carriage, extends horizontally adjacent to the top of the carriage and has its free end rotatably mounted in the bracket 51 fixedly mounted on the framework, and a sprocket secured thereon adjacent to the bracket. A chain 52 connects the sprocket 48 with the pulley on the shaft 49. A manually operated wheel 53 connected to the gear box 50 to rotate the shaft 49, controls the mechanical speed controller.

An operator's seat 54 is suitably mounted on the carriage 10 and extends upwardly and outwardly therefrom, positioning the operator within reaching distance of the controller 38 and the wheel 53.

As mounted on the tracks or rails, the framework or carriage 10 extends outwardly therefrom, the lower wheels 14 and 15 supporting the carriage while the upper wheels 27 and 28, engaging the upper rail, keep it in proper position.

The nature of the work requires that the spreading machine is able to be run at different speeds. The drive as hereinabove described and illustrated, is for use with A. C. current, requiring the mechanical speed controller to effectively

vary the speed of the motor and thus of the carriage and spreading machine.

In the operation of the drive, the operator seats himself or herself on the carriage and starts the motor by operating the controller 38 by means of the handle 55, the power being transmitted to the driving wheel 14 of the carriage through the belt 44 actuating the speed reducer shaft to which the shaft of the driving wheel is connected. The operator stops or reverses the carriage by means of this controller. For a variation in speed the operator manipulates the wheel 53 causing the chain 52 to turn the threaded shaft 46, to which the motor is connected, and to draw the motor back, the belt 44 being tightened on the variable speed pulley 42. This tightening of the belt causes the two cones comprising the variable speed pulley to expand and thereby permitting the belt 44 to ride further down in the cones. The result of this is a reduction in the effective diameter of the variable speed pulley, thereby effecting a reduction in speed, or conversely causing the motor to be moved forward to increase the speed.

Instead of using a variable speed pulley 42 on the motor as hereinabove described, a speed reducer with variable speed feature in one compact unit, as indicated by the numeral 60 in Figure 6, may be used, the only difference in the set-up of the carriage being that the chain 61 is connected to the variable speed pulley or mechanism contained in the reducer unit 60, the same being operated by manual manipulation of the wheel 62, the motor in this case being rigidly mounted on the carriage.

For use with D. C. current, the carriage as indicated in Figure 5, supports a controller 65, the handle 66 of which starts, stops and controls the speed of the motor 67, the motor being put in reverse by means of the lever 68. The motor in this case being rigidly mounted on the carriage, the V-belt 69 connecting the pulley 70 on the motor with the pulley 71 connected to the speed reducer 72 to actuate the driving wheel 14 of the carriage. This carriage is of course, provided with a seat for the operator, and is otherwise the same as hereinabove described.

The particular manner of support of the carriage, by the rails 26 and 32, permits it to be suspended above the floor, keeping the floor free of obstructions.

It is of course understood that modifications and ramifications may be made without in any way departing from the spirit of the invention as hereinabove described and illustrated.

What I claim is:

1. In a drive for cloth spreading machines, a cutting table, a cloth spreading machine movably supported on said cutting table, an upper rail and a lower rail fixedly located with respect to one side of said cutting table, a carriage comprising a pair of supporting wheels and a pair of retaining wheels, said supporting wheels being rotatably journaled to the lower portion of said carriage at the inside thereof and adapted to travel on said lower rail, said retaining wheels being rotatably journaled in a horizontal plane to the upper portion of said carriage at the inside thereof and adapted to engage said upper rail, a motor mounted on said carriage and suitably connected to an electric power source, an operator's seat supported on said carriage, a drive pulley fixedly secured on the shaft of said motor, a speed reducer unit, a driven pulley

fixedly mounted on the shaft of said speed reducer unit, a belt connecting said drive pulley and said driven pulley, means connecting said speed reducer unit with one of said supporting wheels thus providing a means of moving said carriage with respect to said upper rail and said lower rail, a controller connected to said motor, a mechanical speed controller mounted on said carriage and suitably connected to said motor, and said mechanical speed controller being manually operated by an attendant riding on said seat.

2. In a drive for cloth spreading machines, a cutting table, a cloth spreading machine movably supported on said cutting table, an upper rail and a lower rail fixedly located with respect to one side of said cutting table, a carriage comprising a pair of supporting wheels and a pair of retaining wheels, said supporting wheels being rotatably journaled to the lower portion of said carriage at the inside thereof and adapted to travel on said lower rail, said retaining wheels being rotatably journaled in a horizontal plane to the upper portion of said carriage at the inside thereof and adapted to engage said upper rail, a mechanical speed controller mounted on said carriage, a motor mounted on said speed controller and suitably connected to an electric power source, an operator's seat supported on said carriage, a variable speed drive pulley fixedly secured on the shaft of said motor, a speed reducer unit, a driven pulley fixedly mounted on the shaft of said speed reducer unit, a belt connecting said variable speed drive pulley and said driven pulley, means connecting said speed reducer unit with one of said supporting wheels thus providing a means of moving said carriage with respect to said upper rail and said lower rail, a controller connected to said motor, and said mechanical speed controller being manually operated by an attendant riding on said seat.

3. In a drive for cloth spreading machines, a cloth spreading machine movably mounted on rails secured on top of a cutting table, a rectangular shaped framework forming a carriage, an upper rail fixedly secured to the side of the cutting table and extending out therefrom, a lower rail fixedly secured to the floor and located out from the side of said cutting table and under said upper rail, a drive wheel located at the rear of said framework and extending out from the bottom inside face of same, a supporting wheel located at the front of said framework and extending out from the bottom in-

side face of said framework, said drive wheel and said support wheel being in alignment with one another, a pair of retaining wheels located on the upper inside face of said framework and extending out therefrom and coinciding in position to said drive wheel and said supporting wheel, said pair of retaining wheels being adapted to engage with said upper rail, said drive wheel and said supporting wheel adapted to engage with said lower rail and to support said framework thereon, a mechanical speed controller base mounted on said framework at the front end of same, a motor slidably mounted on said speed controller base and suitably connected to an electric power source, a speed reducing unit, a pulley fixedly secured to the outer shaft of said speed reducer unit, a variable speed pulley mounted on the shaft of said motor, a belt connecting said variable speed pulley on said motor with said pulley on said speed reducer unit, said drive wheel suitably connected to the inner shaft of said speed reducer unit thus providing a means of moving said framework along said lower rail and said upper rail, a controller mounted on said framework and adapted to control said motor, a metal hinge member securing said framework to said cloth spreading machine and adapted to absorb irregularities which might exist or develop in the relative position of said lower rail and said cutting table, an operator's seat suitably mounted on said framework, a chain drive mechanism mounted on said framework and connected to the under side of said motor through an aperture in said mechanical speed controller base and adapted to be manually operated by a person occupying said seat, said motor being adapted to move backward or forward on said speed controller base by the operation of said chain drive to change the effective diameter of said variable speed pulley and thereby effect a change of speed of said motor and said framework.
